UNITED STATES PATENT OFFICE.

EDMUND B. CARNS, OF NEW YORK, N. Y.

AIRCRAFT CHASSIS.

Application filed June 17, 1927. Serial No. 199,570.

My invention relates to improvements in air craft and particularly to airplanes, and to a chassis attachment therefor. The object of my invention is to produce a strong, simple 5 chassis attachment for an airplane which is suspended on a wing and which is adapted to swing upward to the wing when the machine is in the air so as to avoid unnecessary air resistance and which is suspended by the 10 cable which hoists it and without other means of fastening, so that when the cable is released, the chassis attachment will drop by gravity to its position with reference to the fuselage, and with its wheels positioned to 15 run on the ground. This means of swinging and releasing the attachment is important because when it becomes necessary to have the chassis attachment ready for use, it must be done quickly and if there are fastenings to 20 release and more or less work to be done before the attachment is free, disastrous results might follow.

My invention is also intended to produce a 25 strong, simple, practical structure in which when the chassis attachment drops to running position on the ground, it will automatically lock itself to the fuselage of the machine, and will also be locked at its upper part so that the running gear will be strong, stable 30 and effective.

The invention is further intended to provide means for swinging the chassis or wheel attachment into a pocket or recess between the spars of the machine wing where it will 35 be out of the way of the air, and further to provide means for closing a part of the pocket against the ingress of too much air. In carrying out this latter feature, I have the closing gate normally open so as to offer no interference 40 with the free dropping of the chassis attachment and to close the gate requires an operation.

My invention is further intended to produce 45 an attachment in which the parts are light but disposed so as to be unusually strong, and in general to produce a light, strong, practical attachment.

Reference is to be had to the accompanying 50 drawings in which similar reference characters represent the corresponding parts in all views.

Figure 1 is a broken front elevation showing 55 my improved attachment applied to an airplane.

Figure 2 is a broken side elevation of the 60 device as applied to the wing of the plane.

Figure 3 is a broken plan of the structure. Figure 4 is a sectional view taken on the line 4—4 of Figure 2, and

Figure 5 is a detail section on the line 5—5 of Figure 1.

The fuselage 10 and the plane or wing 11 may be of any usual or approved kind, and I have shown the chassis attachment 12 on one side only of the machine, but it will be understood that the other side will be exactly similar. The frame 12 of the attachment is hinged as at 14 to the wing 11 and is arranged to swing into a pocket or bay formed between the spars 15 of the wing. The frame 12 is made of tubular parts for lightness, and has a top bar 13 hinged at 14 as above described, and this has opposite to it and on the same horizontal plane a bar 13', the two being connected by cross bars 13'' to form an essentially rectangular top to the frame as this facilitates its fastening, but it will be understood that the form of the frame may be changed without affecting the invention. The frame 12 has two side parts formed of the tubes 15' arranged in pairs to straddle the wheel 21 as presently described, and the tubes of each pair converge downwardly and are connected by cross tubes 16 so that the cross tubes 16 of the frame lie on opposite sides of the wheel 21. Each pair of side tubes 15' is also connected by a cross tube or bar 17, and on each side of the frame 12 the members 16 and 17 are connected by the vertical pair of tubes or members 18 which act as guides and form a runway for the boxes 19 of the axle 20 which is connected as usual with the wheel 21.

To provide for snubbing the wheel when the machine lights and for absorbing shock, the following arrangement is used. Each box 19 connects with an upwardly extending tube or rod 22 which at its upper end connects with a cross-head 23, and the latter connects with the piston rod 24 of a conventional dash pot 25. The cross-head 23 also connects at opposite sides with the rods or members 26 which have their end portions 27 adapted to slide on the vertical members 28 which connect the cross bars 17 with the top parts 13 and 13' of the frame 12.

The members 26 and 16 are connected by a bank of rubber bands 29, the tension of which is opposite to that of the dash pot piston, and it will of course be understood that springs might be substituted for the bands 29, but the latter are better in practice. Thus it will be

seen that with the landing shock the action causes the boxes 19 to move up against the pressure of the piston rod 24 in the dash pot 25 and against the tension of the spring elements 29 so that these elements and the piston in the dash pot act in the customary snubbing way against each other so as to absorb the excessive shock of landing. This action of opposed spring and dash pot is old but the particular arrangement I show is believed to be novel.

When the chassis attachment swings down into position to run on the ground it must be very substantially held on account of the strain upon it, and to this end I provide for locking it from its free end and also at the top. To this end I arrange on the side next to the fuselage 10, a brace which is preferably in the form of a tripod 30 as shown, comprising tubular members 32 and 31 connecting respectively with the lower corners of the frame 12 and with the cross bar 17 on the inner part of the frame. These members 31 and 32 merge at their outer ends in a socket member 33 which swings into engagement with a stud 34 on the fuselage, and the stud is disposed substantially in the arc represented by the swing of the frame 12 so that the socket 34 will automatically swing to position over the stud. Any suitable latching or automatic locking attachment can be used to fasten the parts 33 and 34 together. I have shown the stud 34 provided with a lateral hole 35 to receive the bolt 36 which slides in a housing and in the wall of the member 33, and is normally pressed by spring 38 so as to engage or enter the hole 35 at its outer end. The bolt 36 is provided with a ring 39 or equivalent means to facilitate fastening a cord or cable thereto so that when the frame 12 is to be swung upward and outward the cable may be pulled and the spring bolt 36 released. The foregoing side lock tends to hold the chassis attachment, that is the frame 12 and connected parts in running position, and to further stiffen the connection I employ bolts 40 which are held in keepers 41 and are spring pressed in the customary manner so that as the frame 12 drops downward it will pass between the bolts 40 and these will spring into position over the outer top part of the frame and lock it in running position. Thus the frame will be locked on the lower and inner side and also at the upper and outer portion and will be very rigidly held. The bolts 40 have means at their outer ends as shown at 41 to facilitate connection with a cable 42 by which the bolts can be pulled outward to release the frame 12 and permit it to swing upward. I have shown cables 42 for moving the bolts, but any suitable means can be employed. The frame 12 can be swung upward by the cable 43 which I have shown running over suitable guides 44 in Figure 1. I have not shown in detail the

cable arrangement for moving the several parts because it will be understood that these can be arranged in a great many different ways to free the several bolts, but the cable 43 is the sole support of the frame 12 when it is in its position in the wing 11 so that when the cable is released by the operator there will be nothing to prevent the chassis attachment, that is the frame 12, from dropping instantly and freely to its position shown in Figure 1.

The under cover of the wing 11 is cut away as shown at 45 to permit the chassis attachment to swing into the bay between the spars 15 and the opening 45 can be closed in part 80 by the gate 46. This is normally, however, held open by a spring 47 connecting with a stud 48 on the gate and with a stud 49 on the under part of the wing so that unless the gate is purposely closed it will be open to permit the chassis attachment to drop and if the cable 51' which controls it is released the gate will slide open. It will be easily understood that the cables 51' and 43 can be moved at one operation and released at one operation. The gate is closed by the swinging arms 50, one of which connects with the cable 51' and these arms abut with plates 51 on the gate 46 and they are connected to a shaft 52 which is pivoted between the spars 15 of the wing. Thus it will be seen that when the cable 51' is pulled, the arms 50 will swing against the abutment or plates 51 to close the gate against the tension of the spring 47, and when the arms and cable are released, the spring will force the gate open.

Assuming that the chassis attachment is swung upward as shown by dotted lines in Figure 1, it will be seen that the attachment will be out of the way of the wing and the pocket in which it lies will be partly closed by the gate 46, but as the cables 43 and 51' are released the gate moves automatically out of the way and the chassis attachment drops by gravity swinging into position to have the socket member 34 locked to the stud 33 on the fuselage 10, that the bolts 40 automatically engage the upper top portion of the frame 12, and that the chassis is therefore instantly and automatically in position for use.

I claim:

1. An airplane having a chassis attachment hinged to swing between the wing and the side of the fuselage of the airplane, and automatic locking means acting when the chassis attachment swings downward and disposed to fasten the lower inner portion of the attachment to the fuselage and the upper outer portion to the wing.

2. An airplane having a chassis attachment hinged to the wing of the airplane and arranged to swing into a pocket in the under side of the wing and to swing downward to a position along side the fuselage, and locking means acting to lock the free part of the

chassis attachment to the fuselage and the upper outer portion thereof to the wing.

3. An airplane having a chassis attachment hinged to swing into a pocket in the frame of the plane and to swing downward along side of the fuselage of the plane, a self opening gate closing over a part of the pocket, and means controlling the gate and chassis attachment which when released permits the gate

10 to open and the chassis attachment to drop.

4. The combination with an airplane having a fuselage and a wing with a pocket therein, of a self opening gate normally held to closing a part of the pocket, a chassis attachment hinged to the wing and adapted to swing into the pocket, and means for swinging up the chassis attachment and releasing the gate

to permit it to open.

5. The combination with an airplane fuselage and wing, the latter having a pocket therein, of a chassis attachment hinged in the wing and adapted to swing into the pocket and also to swing down opposite the fuselage, a brace on the inner free part of the attachment

25 adapted to automatically lock against the fuselage, and a locking attachment for securing the upper outer part of the chassis to the wing.

6. The combination with an airplane having a fuselage and a wing, with a pocket in the wing, of a chassis frame hinged at its upper inner parts to the wing and adapted to swing downward opposite the side of the fuselage,

means for automatically locking the frame to the fuselage, and locking attachments automatically engaging the upper outer portions of the frame when the latter is swung downward.

7. The combination with an airplane having a fuselage and a wing with parallel spars therein, of a chassis frame pivoted between the pair of spars and arranged to swing into the bay between the spars and to drop to position along side the fuselage, releasable means for suspending the free part of the chassis attachment between the spars, a self opening gate to partly close the bay in response to the same releasing means as the chassis and automatic means for fastening the chassis in its dropped or running position.

8. The combination with an airplane having a fuselage and a wing, of a swinging chassis frame pivoted to swing into a recess in the wing and adapted to drop into running position, means for automatically locking the said frame to the fuselage when the frame is dropped, a wheel mounted in vertically sliding boxes in the frame, a cross head connected to the boxes, yielding means retarding the upward movement of the cross head, and a dash

50 pot above and connected to the cross head.

In testimony whereof, I have signed my name, to this specification this 3rd day of June, 1927.

EDMUND B. CARNS.
